UNITED STATES PATENT OFFICE.

WILLIAM H. BASENBERG, OF BIRMINGHAM, ALABAMA.

JOURNAL-POLISHER.

1,215,238.

Specification of Letters Patent. Patented Feb. 6, 1917.

Application filed June 8, 1916. Serial No. 102,605.

To all whom it may concern:

Be it known that I, WILLIAM H. BASENBERG, a citizen of the United States, residing at Birmingham, in the county of Jefferson and State of Alabama, have invented 5 certain new and useful Improvements in Journal-Polishers, of which the following is a specification, reference being had therein to the accompanying drawing.

10 This invention relates to journal polishers and has for its principal object the production of a polisher which may be easily and quickly attached to a journal for the purpose of permitting the same to be efficiently smoothed throughout its entire length in order to produce the best possible bearing 15 while in operation.

Another object of this invention is the production of a simple and efficient journal 20 polisher whereby the sections may be adjusted tightly upon the journal to suit the convenience of the operator, thereby allowing slight wear upon the journal as well as upon the polishing segments to be taken up 25 and thereby permitting the polisher at all times to firmly clamp the face or periphery of the journal.

With these and other objects in view, my 30 invention consists in certain novel combinations, arrangements and construction of parts as will be hereinafter fully described and claimed.

In the drawings:

Figure 1 is a side elevation of the journal 35 polisher which may be used in connection with a machine driven by compressed air.

Fig. 2 is a front elevation of the polisher the driving brace being removed therefrom.

Fig. 3 is a vertical section taken on line 40 3—3 of Fig. 2 looking in the direction of the arrow, a portion of the driving brace being shown in section.

Fig. 4 is a top plan view of the journal 45 polisher.

Fig. 5 is a section taken on line 5—5 of Fig. 2.

Fig. 6 is a side elevation of a portion of the brace used in connection with the present invention for connecting the guiding 50 mechanism with the polisher.

Fig. 7 is an end view of the structure shown in Fig. 6.

Fig. 8 is a section taken on line 8—8 of Fig. 2 showing the driving fork in place.

Fig. 9 is a section taken on line 9—9 of Fig. 2.

Fig. 10 is a section taken on line 10—10 of Fig. 2 showing the driving fork in place.

Fig. 11 is a side elevation of a hand brace which may be used in connection with the driving fingers of the brace for operating the journal polisher.

Fig. 12 is a section taken on line 12—12 of Fig. 11.

Fig. 13 is a side elevation of the joint connection between the driving brace and the driving fingers or arms.

By referring to the drawings, it will be seen that 1 designates the primary section of the journal polisher which primary section 70 is used in connection with the auxiliary section 2. A metallic strap 3 is secured to each of the sections 1 and 2 and is pivotally connected at the rear end by means of a hinged joint 4. The metallic strap which is carried 75 by the auxiliary section 2 is provided with a projecting lip 5 having a rolled portion 6 formed at the outer end thereof within which rolled portion 6 is pivotally mounted a rectangular link 7. The strap 3 which is carried 80 by the primary section 1 is also provided with a projecting end 8 which projecting end is engaged by means of a tightening screw 9 carried or threaded through the bearing portion 10 of the link 7. It will 85 therefore, be seen that the journal polisher or that is say, the sections of the journal polisher may be drawn tightly around a journal for polishing the same. Each of the sections 1 and 2 is provided with a polishing 90 band 11 upon the inner face thereof which band is preferably formed of leather or other suitable material and is preferably semi-circular in shape. A similar band 11 is carried by each of the primary and auxiliary sections 95 of the polisher as illustrated in Fig. 2 of the drawings. The ends of each band 11 abut against an abutment plate 12 countersunk in the respective ends of the primary and auxiliary sections 1 and 2. Abutment 100

plates 13 are also secured to one side of each section 1 and 2 and constitute stops for the bands 11. Buttons 14 are pivotally secured to the opposite side in each of the primary 5 and auxiliary sections and may be swung so as to have their ends overhang the edges of the bands 11 as illustrated in Fig. 3 of the drawings, thereby holding the bands 11 in place, and these bands may be easily removed to permit new bands to be replaced 10 therefor when so desired.

It should be understood further that suitable grinding material may be used in connection with the leather bands 11 such 15 as emery dust and oil or carborundum dust to suit the convenience of the operator.

A driving fork 15 is adapted to engage the journal polisher and is provided with a plurality of driving fingers 16 which fingers 20 are provided with laterally extending lugs 17, these lugs 17 are adapted to fit within the notches 18 formed upon one face of the sections of the journal polisher as illustrated in Fig. 2, the outer ends 18' of the fingers 16 25 passing through the apertures 19 formed in the sections of the journal polisher.

Buttons 20 are pivotally secured to the outer face of the sections of the journal polisher and are adapted to be swung so as 30 to overhang the laterally projecting lugs 17 carried by the arms 16 firmly retaining the arms in engagement with the sections of the journal polisher, thereby preventing the arms from being accidentally detached 35 therefrom.

It should be understood that the driving fork 15 is provided with a threaded socket 21 which threaded socket may be connected either directly to a pneumatic driving machine 22 such as illustrated in Fig. 1 of the drawings, or may be connected to a hand brace 23 shown in Fig. 11 by means of attaching the connecting joint 24 to the driving fork 15 as illustrated. This connecting 40 joint 24 is provided with projecting threaded lugs 25 which threaded lugs fit within said threaded sockets 21 formed in the driving fork 15. From the foregoing description it will be seen that a very simple and 45 efficient means has been produced for driving the journal polisher and also connecting the driving mechanism to the journal polisher so as to permit the driving mechanism to be readily attached or detached 50 from the journal polisher. It should be further understood that the leather bands 11 may also be readily removed from the polisher when desired for the purpose of permitting the bands to be renewed when 55 the same have become worn.

What I claim is:

1. A journal polisher of the class described comprising a plurality of sections, means for hingedly connecting said sections

together, tightening means carried by one 65 section and engaging the other section for binding the same upon a journal, and a removable polisher carried by each section.

2. A journal polisher of the class described comprising a plurality of sections, a metallic band secured to the outer face of each section and hingedly connecting said sections together, each band provided with a projecting lip at the outer end thereof, a link connected to one of said projecting 70 lips, a binding screw carried by said link and adapted to draw said sections together, a detachable polishing band secured to the inner face of each section. 75

3. A journal polisher of the class described comprising a plurality of sections, means for tightening said sections upon a journal, a polishing band secured to each section, an abutment plate secured to one face of each section for preventing the accidental displacement of said band upon one side of said polisher, and pivoted buttons carried by the opposite side of each section and releasably engaging said polishing bands for detachably holding said bands in 80 engagement with said sections. 85

4. A journal polisher of the class described comprising a plurality of sections, means for tightening said sections upon a journal, a polishing band secured to each 90 section, an abutment plate secured to one face of each section for preventing the accidental displacement of said band upon one side of said polisher, pivoted buttons carried by the opposite sides of each section 95 and releasably engaging said polishing band for detachably holding said bands in engagement with said sections, and abutment plates carried by the ends of each section and engaging the respective ends of said 100 polishing bands. 105

5. A journal polisher of the class described comprising a polishing body, said polishing body provided with sockets formed therein, laterally extending pockets communicating 110 with said sockets, and driving means fitting within said sockets and pockets for detachably engaging said polishing body.

6. A journal polisher of the class described comprising a polishing body, said body provided with a plurality of transversely extending apertures, said body also provided with shallow pockets communicating with said apertures, a driving fork, means for driving said driving fork, said 115 driving fork provided with a plurality of fingers fitting within said apertures, lugs carried by said fingers and fitting in said pockets, and means for releasably holding 120 said lugs in said pockets. 125

7. A journal polisher of the class described comprising a polishing body, said body provided with a plurality of trans-

versely extending apertures, said body also provided with shallow pockets communicating with said apertures, a driving fork, means for driving said driving fork, said 5 driving fork provided with a plurality of fingers fitting within said apertures, lugs carried by said fingers and fitting in said pockets, buttons pivotally secured to said body and adapted to be swung to overhang said lugs for releasably holding said fingers 10 in engagement with said body.

In testimony whereof I hereunto affix my signature.

WILLIAM H. BASENBERG.
